UNITED STATES PATENT OFFICE.

JOHN A. WARNER, OF FURNACEVILLE, NEW YORK.

EVAPORATOR.

SPECIFICATION forming part of Letters Patent No. 240,626, dated April 26, 1881.
Application filed February 10, 1881. (No model.)

To all whom it may concern:

Be it known that I, JOHN A. WARNER, of Furnaceville, in the county of Wayne and State of New York, have invented a new and Improved Evaporator, of which the following is a specification.

The object of this invention is to provide an improved device for drying fruit and vegetables and evaporating liquids.

10 The invention consists of two upright fixed cylinders placed concentrically one within the other, the outer cylinder having rollers fixed on its inner face in such a position as to form a disconnected spiral track for the outer ends 15 of the evaporating-trays, and the inner cylinder being provided around its outer face with a continuous spiral for the inner ends of the evaporating-trays.

Figure 1 is a sectional elevation of the device. Fig. 2 is a top view of the cylinders with brace removed.

Similar letters of reference indicate corresponding parts.

In the drawings, A indicates the inclosing-furnace or hot-air chamber containing the improved evaporator.

B represents the outer cylinder, supported in an upright position in and upon the hot-air chamber A, and having, preferably, a concave bottom for the purpose of strength, and having its top fully open for the withdrawal of the trays and for the escape of the moisture evaporated from the contents of said trays. Said cylinder B has secured on its inner face 35 rollers B', arranged in such a manner as to form spirals from bottom to top thereof.

C represents the inner cylinder, fixed centrally in an upright position in the cylinder B, and provided around its outer face with a continuous spiral track, C'.

D represents the vertical shaft extending through the cylinder C, and having a lower bearing, at a, in the bottom of the cylinder B, and an upper bearing, b, in a brace, D', that 45 extends across the top of the cylinder B.

Securely fixed upon the shaft D, above and below the cylinder C, are the radial arms E E; and F are the upright arms connecting the upper with the lower arms, E, in pairs.

50 G G represent the evaporating-trays, of sec-

tor shape, each tray G having a stud or spindle, c, projecting in a horizontal plane from its smaller end, on which stud or spindle c is a vertically-revolving roller, d.

It is designed to slowly revolve the shaft D 55 and attached arms E F by means of suitable gear or other devices, which may be connected either with the top or bottom of the said shaft D. The shaft D being put in motion, the trays G G are introduced, one at a time, into the 60 cylinder B, through its opening f, near its bottom, said trays G being arranged with their broader ends resting on two or more of the rollers B', while the roller d of each tray G rests on the spiral track C' of the cylinder C. 65 As the shaft D revolves the arms F push the trays G, as the latter are introduced through the opening f, spirally upward to the top of the cylinder B, whence they are withdrawn, the speed of the shaft D being made fast or 70 slow, according to the time required for the exposure of a tray, E, and its contents to the air passing up through said cylinder B.

It will be seen that by this arrangement—by moving the trays E upward in a spiral—a 75 much longer exposure of the trays and their contents to the heated air of the inclosing-cylinder can be had than if said trays were raised at the same speed in a vertical plane, as in ordinary evaporators.

Having thus fully described my invention, I claim as new and desire to secure by Letters Patent—

1. An improved evaporator, constructed substantially as herein shown and described, consisting of outer and inner cylinders, B C, provided with spirally-arranged rollers B' and spiral track C', respectively, and shaft D, provided with arms E F, substantially as herein set forth.

2. The combination, with the outer cylinder, B, provided with spirally-arranged rollers B', and inner cylinder, C, provided with spiral track C', of the trays G, provided with attached rollers d, substantially as herein shown and described.

JOHN ALBRIGHT WARNER.
